UNITED STATES PATENT OFFICE.

EARL BARNEY, OF SCHENECTADY, NEW YORK.

DESIGN FOR A BROODER.

SPECIFICATION forming part of Design No. 23,168, dated April 3, 1894.

Application filed February 24, 1894. Serial No. 501,425. Term of patent 7 years.

To all whom it may concern:

Be it known that I, EARL BARNEY, of Schenectady, in the county of Schenectady and State of New York, have invented a new and original Design for Brooders, of which the following is a full, clear, and exact description.

Reference is to be had to the accompanying drawing forming a part of this specification, in which is shown a perspective view of a brooder embodying my new design.

The leading feature of my design consists of the conformation shown, to wit:—the side walls disposed vertically presenting an angular figure, and the roof of novel design comprising three panels or members, of which the largest central member *a* has a slight pitch toward the front member *b*, which latter has

a forward pitch of steeper inclination than the pitch of the member *a* and forms an angle therewith, and is overlapped by the latter. 20 The rear panel or member *c* of the roof has a pitch in a rearward direction, that is, the reverse of the members *a* and *b*, and terminates at its upper end at a point below the rear end *a'* of the panel *a* and inward from the upper 25 edge of the latter.

I claim—

The design for a brooder herein shown and described.

EARL BARNEY.
